UNITED STATES PATENT OFFICE.

PATRICK B. DELANY, OF NEW YORK, N. Y., ASSIGNOR TO THE STANDARD MULTIPLEX TELEGRAPH COMPANY, OF SAME PLACE.

METHOD OF EFFECTING ELECTRICAL SYNCHRONOUS MOVEMENTS.

SPECIFICATION forming part of Letters Patent No. 322,691, dated July 21, 1885.

Application filed August 21, 1884. (No model.)

To all whom it may concern:

Be it known that I, PATRICK B. DELANY, of the city, county, and State of New York, have invented an Improved Method of Correction of Electrical Synchronous Movements, of which the following is a specification.

My invention consists in an improved method of correction of electrically-connected synchronously-moving apparatus, by which both apparatus at the end of the line are simultaneously corrected whenever either of them runs out of time.

The accompanying drawing is a diagram view illustrating two connected stations equipped with apparatus for carrying out my invention.

Letters Patent No. 286,278, of October 9, 1883, fully describes the actuation of the armature-disk A, on the spindle of which the trailing finger *a*, which traverses the table of contacts B, is carried. In that patent also the operation of the motor-magnet A', the vibrator-magnet A², and the fork A³, and the various circuits and attachments are fully and elaborately illustrated and described, and further description is unnecessary, reference being made to said patent for full information as to details.

In Letters Patent No. 286,281, of October 9, 1883, I have fully described the arrangements of contacts and circuits herein shown, by which a correcting impulse of electricity is sent from one station to the other whenever the apparatus at a distant station runs out of time; and have also described and claimed in said patent the method of controlling the speed of the mechanism at the distant corrected station by throwing a resistance into or out of the vibrator circuit.

The arrangement of contacts and circuits and group of instruments V shown in the accompanying drawing are identical with those shown and described in said patent, and do not, therefore, need particular description here, as their operation will be obvious upon a mere inspection of the drawing. Thus, if while the trailing finger *a* at station X is on the 9 connected with the battery C B, the finger at station Y should be moving fast enough to bring it upon the extended 10, a correcting impulse of electricity would pass from the correcting-

battery C B through the 9-contact at station X, trailing finger, line, trailing finger at station Y, and 10 contact to the group of controlling-instruments V, and the resistance R would be shunted or cut out of the vibrator or fork-circuit so as to increase the electro-magnetic power of the fork-magnet in that circuit and slow the speed of rotation of the trailing finger so that it would drop back into proper position.

The operation is precisely the same when an impulse is sent from the correcting-battery C B at station Y to the group of correcting-instruments V at station X. The correction is therefore reciprocal; and although the corrections are shown as acting by retardation, they could obviously be arranged to act by acceleration, as is fully set forth in the patent last mentioned.

Thus far the arrangement described is exactly the same as that shown in said patent. My present invention, however, involves a different method of operation, and consists in simultaneously correcting the apparatus at both stations. Thus (having reference to the latter plan) when a correcting impulse is sent, say, from station X to retard the apparatus at station Y, the same impulse is at station X utilized to accelerate the instrument at that station, so that a correction of acceleration at one station and of retardation at the other will act more vigorously and promptly to control the instruments.

The operation is the same when a correcting impulse is sent from Y to X, and I will now describe it. We will again suppose that the apparatus at Y is running faster than at X, and that a correcting impulse is transmitted, as before described, from the correcting-battery C B at X to the group of controlling-instruments at Y to retard the apparatus at Y. The same impulse, however, is made effective at X to accelerate the apparatus there in the following manner: The line from the battery C B passes through the coils of a relay, S, and thence to the 9-contact, as shown. The armature of this relay controls a local circuit, in which the coil of a second relay, T, is placed. A shunt-circuit, *s*, controlled by the armature of the relay T, normally shunts the resistance R' out of the fork-circuit *f*, as

clearly shown in the drawing. When, however, a correcting impulse of electricity from the battery C B energizes the relay S, its armature is drawn to its front stop, its local circuit is broken, and the relay T demagnetized, so that its armature falls from its front stop, thus breaking the shunt s and causing the fork-circuit f to run from the local battery L B through the resistance R'. This resistance is therefore thrown into the fork or vibrator circuit whenever a correcting-impulse is sent from the battery C B. The effect is to reduce the electro-magnetic power of the magnet of the fork-circuit, which results in a consequent increase of rate of vibration and increase of speed in the rotation of the trailing finger. The conditions are precisely the same when a correcting impulse is sent from station Y to station X. At station Y, however, I have shown a somewhat modified arrangement for accomplishing the same result, in which I dispense with a resistance in the controlled fork-circuit f when a correcting impulse of electricity is sent out from that station, by momentarily interrupting said circuit when the armature of the relay T leaves its front stop. The effect and principle of operation are precisely the same as at station X. The momentary interruption of the fork-circuit at Y introduces an infinite resistance into the circuit. The decrease in amplitude of the vibration of the fork would be slight, as the interruption of the circuit is but momentary and the normal rate of vibration of the fork would prevent too great a decrease in amplitude.

I have shown different arrangements at each station for the purpose of convenience of illustration. In operation, however, it would be better to have the arrangements alike at both stations. I prefer to operate with the resistance R', as shown at station X, as I consider this the most efficient arrangement for practical use. The apparatus may, however, be worked by interruptions of the fork-circuit. Obviously, whenever the apparatus is to be

accelerated the fork-circuit may be interrupted; and, therefore, if the group of instruments V was arranged to accelerate, the fork-circuit might be interrupted at that point and the resistance R dispensed with.

Further description is deemed unnecessary. 50

I have shown my present invention embodied in the form deemed by me best adapted to the purpose. It may, however, be varied without departing from the spirit of my invention, 55 which contemplates, broadly, the method of operation consisting in simultaneously correcting at both stations, by acceleration at the station from which the correcting impulse is sent, and by retardation at the distant station, or 60 vice versa.

No claim is made herein to the general organization of apparatus, as that constitutes the subject-matter of my original application, No. 122,054, filed February 26, 1884, of which this 65 case is a division.

I claim as my invention—

1. The method of synchronizing apparatus, which consists in sending a correcting impulse of electricity from one station to a distant station whenever the apparatus run out of synchronization, utilizing said impulse at the distant station to correct the speed of the apparatus at that station and simultaneously utilizing the same impulse to correct the speed of the apparatus at the station from which the impulse is sent out. 70 75

2. The method of synchronizing electrically-connected apparatus, which consists in independently actuating such apparatus, and then, 80 whenever either apparatus runs out of time with the other, simultaneously retarding the speed of one apparatus and accelerating that of the other to bring them together again.

In testimony whereof I have hereunto subscribed my name. 85

PATRICK B. DELANY.
